UNITED STATES PATENT OFFICE.

RUSSELL THAYER, OF PHILADELPHIA, PENNSYLVANIA.

ELECTRICAL REVOLVING BRUSH.

SPECIFICATION forming part of Letters Patent No. 393,192, dated November 20, 1888.

Application filed September 7, 1887. Serial No. 248,998. (No model.)

To all whom it may concern:

Be it known that I, RUSSELL THAYER, a citizen of the United States, residing at Philadelphia, State of Pennsylvania, have invented 5 a new and useful Improvement in Revolving Brushes, of which the following is a full description thereof.

My invention consists in a novel construction by which the brush is readily caused to 10 revolve, and by its friction accomplishes the desired result, such as cleaning horses, polishing, or any other operation in which a rubbing-surface is used.

In the drawings, Figure 1 represents an outside view of one form of my improvement; 15 Fig. 2, a section on line xx , Fig. 1. Fig. 3 represents a sectional view of one modified form of my improvement, in which the axis of the motor is shown in a vertical position, and the 20 brush is connected at the lower end of and revolves with said axis. Fig. 4 is a plan view of Fig. 3.

C represents the armature, and D the magnets forming an electric motor. The current 25 comes from any desired source through the wires b, which are preferably surrounded by an insulating material. The wires are carried through the handle B, and are connected with the frame d, by means of which the current is 30 carried to the motor. The magnets are insulated from the frame d by the insulating-surfaces d'd'. The brush-frame a of the brush A is connected with and insulated from the frame d. This brush may be constructed of any material 35 in accordance with the desired use. The brush A being connected with the shaft of the electric motor, when the current is sent through, the motor-shaft revolves and the brush is carried around with it, and upon the brush being 40 presented to the surface of the substance to be operated upon its revolution causes it to perform the desired work. If desired, the shaft and armature may be fixed and the magnets revolve, and by their revolution operate the 45 brush; or the magnets may be fixed, and a hollow armature revolving about them may be used to operate the brush.

My invention may be used for polishing surfaces of any character and for performing any work which requires a metallic or other character of brush, the term "brush" in this specification and claims, besides its ordinary meaning, being intended to refer to any frictional surface, such as emery-cloth.

If desired, the frame d may be made of insulated material. While I consider the construction as illustrated in the accompanying drawings as desirable forms, yet I do not intend to limit myself to the specific forms so illustrated, as it is obvious that many other 55 specific means of connecting the current source with the electric motor may be used, and also various differences of construction may be used without departing from my invention. I can replace the bristles of the brush by the use 60 of emery or other frictional surface without 65 departing from the invention.

Having now fully described my invention, what I claim is as follows:

1. In combination, an electric motor, a brush surrounding said motor, a source of electric-current supply, and means to connect said electric-current supply with the motor.
2. In combination, an electric motor, a brush attached to, insulated from, and revolving with said motor, a source of electric-current supply, and means to connect said electric-current supply with the motor.
3. In combination, an electric motor, a brush attached to and revolving with said motor, a source of electric-current supply, and means to connect said electric-current supply with the motor.
4. In combination, an electric motor, a brush attached to and revolving with said motor, a source of electric-current supply, frame d, and handle B, and means to connect the source of electric-current supply with the motor, all constructed and operated substantially as and for the purpose specified.

RUSSELL THAYER.
